UNITED STATES PATENT OFFICE.

WILLIAM F. DUNLOP, OF NEW YORK, N. Y.

ARCH SUPPORT.

Application filed December 15, 1924. Serial No. 756,106

My present invention pertains to arch supports, and it consists in an arch support possessed of certain definite and clearly defined advantages as hereinafter set forth in detail.

5 In the accompanying drawings, forming part of this specification:—

Figures 1, 2, and 3 are views illustrative of a shoe in which one embodiment of my invention is incorporated as a permanent and 10 hidden part of the shoe, Figures 1 and 2 being longitudinal vertical fragmentary sections and Figure 3 a vertical transverse section.

Figures 4 and 5 are enlarged plan views of different embodiments of my invention, the 15 plane of Figure 1 being designated by the line 1—1 of Figure 4 and the plane of Figure 2 being designated by the line 2—2 of Figure 4.

Figure 6 is a transverse section of the arch support shown in Figures 1 to 4, said Figure 20 6 being taken in the plane by the line 6—6 of Figure 4.

Similar numerals designate corresponding parts in Figures 1, 2, 3, 4 and 6 to which reference will first be made.

25 My novel arch support 1 is formed of one piece of vulcanized rubber or of any other material like vulcanized rubber, that is capable of being molded and possessed of resiliency.

30 In Figures 1 to 3, I show the said arch support 1 as permanently arranged in a shoe between the inner sole 2 of the shoe and the soft leather covering 3 superposed on the inner sole 2 and having upwardly directed side 35 flanges 3*. The arch support incorporated in the shoe as stated is generally maintained in position and against casual movement by its interposition between the inner sole 2 and the covering 3, though when desired the said 40 arch support may be provided with a brad 4 such as shown in Figure 6, the said brad 4 having an enlarged portion embedded in the arch support 1 at the time of molding and also having its shank pendent from the underside of the arch support so as to take into the inner sole 2. I would have it understood, however, at this point that the brad 4 is designed more particularly for use when the arch support is merely placed in a shoe inasmuch as the purpose of the brad is to prevent 45 casual shifting or change of position of the arch support.

In carrying my invention into effect where an arch provision is to be made for a deformed 50 or a defective foot, I first take an impression

of the foot to be supported, in any compound or any other plastic material suitable to the purpose, and then mold a last of appropriate material in the matrix indicated. I then appropriately shape the rubber on the said last, and 60 while the rubber is held under pressure against the last, I vulcanize the rubber so that the arch support of vulcanized rubber will at its upper side have the shape of and will snugly and correctly fit the foot from which the impression is taken. It will also be understood in this connection that in conformity with the underside of the arched or instep portion of the human foot the arch support 1 will be 65 in general longitudinally convex at its upper side and longitudinally concave at its underside, while transversely the arch support will be concave at its upper side and convex at its underside, these latter features being due to the fact that in all cases the arch support 70 will have side flanges 5 and 6 possessed of resiliency and constituting important features of my invention.

In the preferred incorporation of the arch support produced and characterized as stated 80 in a shoe as a permanent and hidden part of the shoe, the inner sole 2 of the shoe is taken in a wet state and is shaped by pressure or otherwise to the underside of the arch support 1, and as the shoe is fabricated the arch 85 support is made in the shoe—i. e., between the inner sole 2 and the soft leather covering 3, the said covering 3 being put in position after the shoe is practically finished.

By virtue of my novel arch support being 90 produced as stated it will be manifest that the arch support will support the foot and will protect all joints and will distribute the pressure throughout the metatarsal region of the foot so that the pushing of any bone out of place will be averted. The arch support characterized as stated will also operate to spread the toes, and the two side flanges 5 and 6 of the arch support will have a massaging action 95 against the foot and at the same time will confine between them and prevent spreading of all of the bones comprised in the metatarsal region of the foot. Again it will be understood that the flanges 5 and 6 of my arch support afford protection at points 100 where deformities or dislocations generally exist, and that the arch support is adapted to rock transversely on its end points or bearings and is also adapted to twist or give torsionally with the result that the arch sup- 105 110

port adequately braces the dislocated or deformed joint or part. At its rear end the arch support 1 is provided with a reduced portion or tongue 1^a, best shown in Figure 4, and this reduced tongue or end portion 1^a is adapted to spring or give when the major portion of the arch support does not spring or give so as to conduce to the comfort of the shoe walker in walking.

10 The arch support 1 is provided at 7 on its underside with a ridge which is generally transverse of the arch support and is employed when the arch support is to be used by a heavy person. The arch support 1 is also 15 shown as provided with forwardly extending ridges 8 at its underside and arranged at opposite oblique angles with respect to each other, the said ridges 8 extending from intermediate side portions of the arch support 20 to the forward end thereof and having their forward ends spaced apart as clearly brought out in Figure 4. The said converging ridges 8 permit of the forward end of the arch support giving or yielding to pressure without 25 the portions reinforced by the ridges 8 giving or yielding to pressure.

In Figure 5, I show an arch support 1^a possessed of all of the advantages ascribed to the support 1 except that the support 1^a is provided with a transverse ridge 7 alone.

30 The practical advantages of the transverse pendent ridge 7 and the forwardly converging ribs 8, will be better understood when it is stated that by virtue of such ridges and 35 ribs, the arch support will be braced thereby and will yield only when subjected to pressure, with the result, the portions at opposite sides of any one ridge will be maintained substantially rigid while the remaining portions 40 will yield in practically the same manner as sand under the foot.

Incident to walking upon a hard flat surface, the ridges will support the foot in an elevated position and pressure upon one side 45 of the foot will bring about pressure on the corresponding side of the arch support which will result in the other side of the arch support being thrown upwardly against the foot. Again, it will be appreciated that due to the 50 ridges and particularly the transverse ridge 7, the arch support is capable of working under the action of the foot so that all portions of the foot are adequately and comfortably supported and the imposition of undue strain on any portion of the foot averted. 55 In this connection, I would have it understood that the transverse or crosswise ridge 7 when employed alone in the arch will always tend to hold the inner and outer por-

tions of the arch support in a position to serve 60 to the best advantage, an arch support equipped with a transverse ridge 7 alone being more particularly designed for a person who has had the outer portion of the foot 65 broken down and being also particularly desirable because of the capacity of the arch support to rock on this ridge as a center.

In the practical use of my invention, the improved device will serve as a support and 70 also as a builder inasmuch as it will rebuild a broken down arch and restore the same to normal condition and support the restored arch in said condition.

Each arch being individual to a person, the 75 arch will be possessed of a particular freedom of motion so that the weight of the person will always be sufficient to cause the arch to give in the direction toward which the force 80 is exerted. Incident to walking on rough ground my device sustains the shock and strain and takes the same off the bones and ligaments or muscles of the foot, and the device reassumes its normal shape when the 85 foot is at rest. In other words my novel device being made to fit the foot when at rest 90 the device gives and yields only when the weight of the wearer is imposed on the device, and hence the slightest motion of the body is imparted to and is reflected in the twisting and bending of the substance of which the 95 device is composed.

When my novel device is shaped in accordance with a young and normal foot, the device 100 when used serves as a natural support so that no bone or ligament is permitted to be distorted and so that the device holds the ball of the foot in such manner that the toes are not cramped or permitted to move downwardly or upwardly, and hence there is no liability of the toes being hurt by the shoe. 105

Having described my invention, what I 110 claim and desire to secure by Letters-Patent, is:—

An arch support for use in a shoe and being formed from a single piece of molded material possessed of resiliency, said support being longitudinally convexed at its upper side and longitudinally concaved at its underside, side flanges included in said support, a pendent ridge portion for said support with de- 115 pressible portions at opposite sides of the ridge portion; the said ridges portion including a transverse ridge at a point intermediate the length of the arch and forwardly converging ridges at the forward portion of the arch.

In testimony whereof I affix my signature.

WILLIAM F. DUNLOP.
